UNITED STATES PATENT OFFICE

HARRY C. TUTTLE, OF LONG ISLAND CITY, NEW YORK

TELEPHONE MUFFLER

Application filed July 1, 1929. Serial No. 375,065.

This invention relates to an instrumentality by means of which a telephone user may speak into a telephone transmitter while persons are within hearing distance of his voice without those persons being able to hear what he is saying and, speaking broadly, may be denominated a telephone silencer or muffler.

Heretofore, for the purpose of enabling telephone users to speak into the transmitter of a telephone without being heard by persons within hearing distance, it has been customary for the person using the telephone to withdraw to a sound-proof booth or to make use of some one of the well known devices permanently attached to a telephone transmitter, known as mufflers.

The provision of a sound proof booth is in the large majority of cases quite impossible and undesirable both by reason of the expense involved and the amount of space required.

There are a number of devices, known as mufflers, which are designed for permanent attachment to the ordinary type of telephone desk set now usually employed in this country but such devices are objectionable to some because, being rather large, they detract from the symmetrical appearance of the telephone set and become tiresome to the eye, as they are usually always in place even though the necessity for their use may arise but rarely.

At the present time, a decided preference is being shown by many for the desk telephone set which is popularly known as the "hand set", that is, one in which the transmitter and the receiver are attached at the opposite ends of a single arm, spaced such a distance apart that the receiver rests nicely in place against the ear, and the transmitter is positioned at a distance from the lips properly to receive sounds issuing therefrom.

The well known forms of silencers designed to be permanently attached to a transmitter were not intended, so far as I am aware, to be used in association with the hand set type of instrument, furthermore, the placing of the ordinary and well known mufflers on such a type of instrument would hamper the placing of the set on its cradle and would

result in a decidedly inartistic structure so that those who have objections to the ordinary telephone when equipped with an ordinary type of muffler would doubtless object to such an extent that the use of a muffler of 55 the ordinary type with the hand set type of instrument would not be commercial.

In order to obviate the objections hereinbefore cited, and to furnish the telephone user with an unobjectionable accessory which may 60 be used as a silencer with the hand set type of instrument, applicant has produced the invention hereinafter to be fully described.

A principal object of applicant's invention is the production of a device which may be 65 used as an accessory to the hand set type of telephone transmitter as a muffler or silencer.

A further object of applicant's invention is the production of a silencer which will be so constructed that it need not and will not 70 be permanently connected to a telephone transmitter but may be temporarily, conveniently and easily connected or associated therewith for the purpose of acting as a silencer.

A further object is to provide a telephone silencer which will be a complete unit in itself, standing on its own base at the correct height to receive the telephone transmitter in the normal position of use.

A further object of applicant's invention is the production of a device of the type specified which will act efficiently as a muffler, in that, it will be so formed that not only will the conversation of the user be inaudible to persons within hearing range but the telephone transmission will be improved because the lips are automatically positioned at the proper distance from the diaphragm of the telephone transmitter and surrounding noises 90 will be excluded from the transmitter.

A further object of the invention is to provide a device of the type specified which will not only function efficiently as a muffler but will also be an artistic utility as a desk piece 95 adapted to perform the functions of some one or more of the well known desk pieces or articles of furniture.

Further objects and advantages will appear as the description of the particular phys- 100

ical embodiment selected to illustrate the invention progresses, and the novel features of the invention will be particularly pointed out in the appended claims.

5 In describing the invention in detail and the particular physical embodiment selected to illustrate the invention reference will be had to the accompanying drawing wherein like characters of reference designate corresponding parts throughout the several views, and in which:

10 Figure 1 is a top plan view of a device embodying my invention; Fig. 2, is a cross-sectional view of the device as shown by Fig. 1, on the plane indicated by the line II—II, viewed in the direction of the arrows at the ends of the line, and also showing the position of the lips and surrounding face contour of a user; Fig. 3, is a cross-section view on the 15 plane indicated by the line III—III of Fig. 1, viewed in the direction of the arrows at the ends of the line, and also showing the position of a telephone instrument when used in connection therewith.

15 My invention contemplates in essence a walled chamber provided with one orifice through which sound issuing from the sound organs of a person may be directed and another orifice into which the diaphragm end 20 of a telephone transmitter may be inserted and rotated and/or pushed to a proper receptive position adjacent to and in line with the direction of the sounds delivered into the sound receiving orifice. With this general 25 construction I have in mind the formation of a walled chamber such that it is self sustaining in that it stands upon its own base in a stable manner free from offensive likelihood to be easily overturned, combined with a 30 graceful and pleasing appearance and one in which the interior contours of the shell are properly designed to direct the sound of the voice, not necessary to transmission on toward a sound absorbing medium in the base 35 and one adapted by its construction to include as a desk utility some one or more of the usual desk conveniences such as a clock, 40 calender or note pad.

45 The full scope of my invention may best be contemplated and understood by reference to the hereinafter given description in connection particularly with the drawings accompanying this specification in which I have particularly illustrated an embodiment 50 of my invention which at the present time is a preferred embodiment thereof, although I desire to have it distinctly understood that the drawings are illustrative only, as the scope of my invention is such that it may 55 be embodied in forms radically and distinctly different from that particularly shown in the drawings and described specifically in the specification.

60 The preferred embodiment of my invention at the present time, as illustrated in the

drawings, is in the form of a hollow shell having a bottom wall, a top wall, a front wall, a back wall and two side walls. From the statement just made it might be supposed that the walls are separate and distinct joined together by suitable means. The structure might well be so made but it is to be understood that although the structure is a walled chamber it is not to be understood that each wall is necessarily separate and distinct from any other or all the other walls because two walls or three walls or even four walls may be formed from a single sheet of material or molded in one piece. In fact, it might well be that the preferred method of making the device would be to make all of the walls integral with the exception perhaps of the base or bottom wall.

65 It is further to be understood that although by using the word walls it seems to indicate that there is a distinct line of division between, say, a side and a back wall, nevertheless, the outside surface of the device can be such that no distinct line of demarcation exists between what may be called a back wall 70 and what may be called the side wall as applicant does not intend to exclude a device so formed as to fail to show distinct edges or corners.

75 In the device as shown in the drawings 95 the right side wall is designated 1; the left side wall, 2; the back wall, 3; and the front wall, 4. The base or bottom wall is designated 5 and the top wall is designated 6.

80 I prefer to have the base or bottom wall 5 removably fitted into a rabbet, as 7, formed in the side walls and in the front and back walls. The bottom wall 5 may well be held 100 in place by various means but I prefer countersunk machine screws as 8 passing through the base and threaded into the ends of the side, front, and back walls.

85 If the side walls and the front and back wall are made integral as by moulding, no 105 means for joining the edges will be necessary but if they are made in several pieces then at the edges at 9 they may be joined by any well known and appropriate means such as 110 soldering or welding.

90 The top wall 6 is to be formed with an 115 orifice 10, best shown in Fig. 1. This orifice will appear somewhat elliptical in plan view as shown in Fig. 1 and the edges will be well rounded, as best shown in Fig. 2, to the end that they will be unobjectionable when 120 pressed against the portion of the face surrounding the lips of a person. The front edge 11 of the orifice 10 will be positioned slightly lower than the rear edge 12 as such construction provides an opening which will 125 best receive, in a sound-tight manner, the portion of the face surrounding the lips. The portion 13 of the orifice and the portion 14 will be at the same level but portions 11 and 12 will each be at a lower level and the 130

portion 11 will be at a lower level than the portion 12. This construction of orifice 10 will best suit the formation of that portion of the face which surrounds the lips of the 5 average user. The manner in which the lips of a user will be positioned and the manner in which the orifice 10 conforms to the face of the user is best shown by Fig. 2 in which a portion of the face of a user is illustrated.

10 The top wall 6 along the lines 15 and 16 curves upwardly and inwardly from the back and from the front in such manner that the line 15, as best shown in Fig. 2, is substantially the arc of a circle. The portion of the top 15 wall which is to the rear of the orifice 10, that is, the portion 17 is dished inwardly as best shown in Fig. 2 so that it offers no impediment to the nose of a user. The front portion of the top wall 6, that is the portion 20 18, is also dished inwardly, as best shown in Fig. 2 so that it does not interfere with the chin of the user.

Although the mouth opening or sound receiving orifice has been described as being in 25 the top wall 6 it is to be understood that in a broad sense the top wall, insofar as this invention is concerned, should be interpreted as meaning the upper portion of the device because applicant does not intend to exclude 30 a construction in which the sound receiving orifice may be so positioned as to well be described as being in the side wall adjacent the top.

The side wall 2 is provided with a circular 35 orifice 19. This orifice is provided with marginate flexible and compressible or resilient material such as soft rubber. This material preferably takes the form of a somewhat annular body provided with a groove 20. As 40 the material is rubber or of the nature of rubber the annular member 21 may be positioned, as shown in Fig. 3, by slightly compressing the walls, positioning it properly in the orifice 19 and then allowing it to expand 45 whereupon the annulus will lock itself in position with the wall 2 situated within the groove 20. The annulus 21 on the portion situated within the chamber 22 is formed with a flange 23 of such shape that it may rest 50 nicely against the front face of the cap of a telephone receiver and the portion intermediate between the flange 23 and the groove 20 is made of such form that it will fit snugly against the side face of the cap of a telephone 55 receiver of the hand set type. The plane of the flange 23 is not parallel with a side wall as 2 but is inclined at an angle thereto, as best shown in Fig. 3, so that the diaphragm opening of the transmitter may be brought 60 just beneath the orifice 10 and be positioned in relation thereto such that the transmitter will be in substantially the same position as regards the lips of a person speaking into the orifice 10 as it would be if the muffler were 65 not being used. The position of the transmit-

ter end of the telephone 24 is shown in Fig. 3 as it would be when a person is talking into the orifice 10.

From Fig. 3, in connection with the herein-before given description, it can be readily understood that one desiring to use the muffler could with his right hand hold the muffler in place on a desk and with his left hand conveniently insert the transmitter end of the telephone 24 into the annulus 21 causing 70 the cap 25 of the transmitter to bear quite firmly against the flange 23 along its inward face and that thereby the transmitter will be properly positioned and then when the telephone conversation is finished it would be 80 as easy to manually remove the telephone 24 as it is to manually insert it into the annulus 21 and manually hold it in position during the conversation. As a diaphragm opening is positioned approximately the same distance from the lips when using the muffler as when ordinarily used the receiver must of necessity be at the proper distance to cooperate with the ear of a person.

As it is desirable to prevent reverberation 90 when sounds are delivered into the wall chamber, applicant provides a chamber the walls of which flare downwardly so that such sound as is not necessary to transmission will be directed downwardly toward a sound absorbing medium 26 placed within the base of the chamber. This sound absorbing medium 26 may be of any desired, appropriate material such as soft felt, wood pulp or the like, and preferably fills the entire space between the walls, rising a considerable distance therein, and is supported by the bottom wall 5.

In selecting the contour, size and proportions of the hollow shell embodying my invention, it is so designed as to flare downwardly with the object of directing the excess volume of sound which is not essential to transmission in a downward direction toward the sound absorbing medium placed in 105 the larger end of the chamber constituting the base where it will be absorbed with the result that its tendency to penetrate the walls and its tendency to reverberate is minimized.

While I have herein illustrated a silencer having sound absorbing material of substantial thickness at its base, obviously the device might be interiorly lined with the sound absorbing material.

While I prefer for theoretical reasons, to have the flare start at the top of the device and gradually increase toward the base, for commercial reasons in minimizing the size I show the side walls 1 and 2 substantially vertical down to about the point 27, as designated in Fig. 3, a little over one half the height, but from that point downwardly to have the sides flare. To the same end, applicant prefers to have the front and back walls formed with a slight flare downwardly beginning at about 120

the junction of the top wall with the front and back walls and increasing slightly in the angle of flare as the walls approach the base. These flares not only serve the useful function of reflecting the sounds within the chamber downwardly to the sound absorbing medium 26 rather than upwardly where they may act upon the diaphragm of the telephone transmitter but also assist in increasing the 10 stability of the device. Furthermore flaring of the side walls toward the base provides a cross-section at that point where the sound absorbing material is placed which is several times the cross-sectional area at the point 15 where the sound is generated by the speaker. Provision is therefore made for the maximum thickness and cross-sectional area of sound absorbing material.

In order to increase the utility and cause 20 it to serve more fully as a desk utility, applicant prefers to mount some one of the well known desk facilities upon one side of the device and to that end illustrated a clock, 28, as mounted upon one side of the device.

25 From the hereinbefore given description in connection with the drawings it will now be readily understood that applicant has produced a telephone muffler which is an accessory rather than an attachment to a telephone; that is so constructed and formed that it is a stable device resting upon its own base and is of such a nature that it may well be used on a desk as an ornament or a utility other than silencer, such as a clock or the 30 like; that it is of substantially artistic configuration and is so constructed that it may properly and efficiently support some one or more of the well known desk conveniences such as a clock; that it is so constructed that 35 the transmitter end of a hand set type of telephone may be easily and conveniently manually inserted and manually held within an orifice thereof and make sound tight connection with a material surrounding and positioned in said orifice; that it is so formed that it fits, in a sound tight manner, the portion of the face surrounding the lips of a person and, consequently, may be used efficiently as a telephone muffler to prevent persons within 40 hearing distance from overhearing a telephone conversation when the device is used; and that the use of the device rather tends to improve telephone transmission than otherwise because the use of the device practically 45 necessitates bringing the transmitter into proper proximity with the lips of the speaker and as the device excludes external sounds and has means for preventing reverberation within itself the telephone transmission is 50 hereby improved.

Although I have particularly described one 55 particular physical embodiment of my invention and explained the principle, construction, and operation thereof, nevertheless, I 60 desire to have it understood that the form

selected is merely illustrative but does not exhaust the possible physical embodiments of means underlying my invention.

While I have shown and described the muffler as adapted especially for use with the 70 so called hand set telephone instrument, it will be understood that it may readily be adapted for use in a similar manner with the type of instrument in which the transmitter is permanently supported upon a standard 75 from the base and the receiver is connected thereto through a cord and hangs upon a cut-out hook on the standard when not in use; and in the appended claims I do not 80 wish the term "manually held" or like expressions to exclude the adaptation of the device to an instrument with which the user is relieved of the necessity for actually holding the transmitter when using it.

What I claim as new and desire to secure 85 by Letters Patent of the United States, is:

1. In a telephone muffler, in combination, material forming an enclosed walled chamber with a substantially flat base and side walls flaring slightly outwardly in a direction toward the base and a top curving inwardly and upwardly, a side wall being formed with an orifice for the reception of a telephone transmitter and the top being formed for the 90 reception of the mouth and lips of a person.

2. In a telephone muffler, in combination, a bottom wall serving as a base; two side walls slightly flaring outwardly toward the bottom wall, one being formed with an orifice for the partial reception of a telephone transmitter; a front wall and a back wall each flaring slightly outwardly toward the bottom wall, a top wall, said top wall curving inwardly and upwardly from each side wall and formed with an orifice formed to receive the mouth and lips of a person with the marginal edges in contact with the portion of the face surrounding the lips and a substantial thickness of a sound deadening material positioned over all the bottom wall.

3. A telephone muffler comprising an upright portable hollow box of a size suitable for desk use and having flaring lateral walls providing a relatively broad base, a mouth opening in the top portion of the box for the reception of downwardly directed sound, an opening in the side wall near the top especially to receive the diaphragm end of a manually held telephone instrument, and sound deadening material in the box below the latter opening and in line with the direction of the sound delivered into the mouth opening.

4. In a telephone muffler, in combination, a bottom wall serving as a base; two side walls slightly flaring outwardly toward the bottom wall, one being formed with an orifice for the partial reception of a telephone transmitter; a front wall and a back wall each flaring slightly outwardly toward the bottom wall, a top wall, said top wall curving in-

wardly and upwardly from each side wall and formed with an orifice shaped to receive the mouth and lips of a person with the marginal edges in contact with the portion of the face surrounding the lips and a sound deadening material positioned on the bottom wall.

5. A telephone muffler for the hand set type of telephone comprising a sound tight walled chamber, said chamber being formed with a sound receiving orifice and an orifice shaped for receiving and making a sound tight connection with the transmitter end of the telephone when manually held therein.

10. In a telephone muffler for the hand set type of telephone, a wall having an orifice therein for the reception of the transmitter end of the telephone, and a bushing within the orifice in said wall, said bushing being formed from flexible material and shaped to receive the transmitter end of the telephone and make a sound tight connection therewith when manually held therein.

15. In a telephone muffler for the hand set type of telephone, a wall having an orifice therein for the reception of the transmitter end of the telephone, and a bushing within the orifice, said bushing being formed from flexible material and having an inwardly extending shoulder for limiting the inward movement of the telephone transmitter and making a sound tight connection therewith.

20. A bushing for the transmitter orifice of a telephone muffler adapted to the hand set type of telephone consisting of flexible material and having a converging inner surface, a circumferential groove near the outer surface to receive the edge of the orifice and an inwardly extending shoulder adjacent the inner surface for limiting the inward movement of the telephone transmitter and making a sound tight connection therewith.

25. A bushing for the transmitter orifice of a telephone muffler adapted to the hand set type of telephone consisting of flexible material and having a converging inner surface, a circumferential groove near the outer surface to receive the edge of the orifice and an inwardly extending shoulder for limiting the inward movement of the telephone transmitter and making a sound tight connection therewith, the plane of the inwardly extending shoulder being substantially parallel to the inner surface of the bushing.

30. In witness whereof, I hereunto subscribe my signature.

HARRY C. TUTTLE.
